MOUNTING MEANS FOR LAMPS IN HEAD-LIGHTS OF AUTOMOBILES

Felix J. Watts, Detroit, Mich., assignor to Utility Patent Trust No. 17,938, Union Guardian Trust Co., Detroit, Mich., a corporation of Michigan

Application October 6, 1937, Serial No. 167,523

5 Claims. (Cl. 240—41)

This invention relates to improvements in the lighting systems of automotive vehicles and more particularly to mounting means for lamps in headlights of automobiles.

5 It is not only highly desirable but necessary that the lamps used in headlights of automobiles are properly and universally so supported in relation to the reflector of the headlight that the relation of the lamp filament to the focus of the reflector be constant or fixed so as to obtain the proper lighting effect. Many devices have been employed for mounting the socket of the lamp upon the rear of the reflector to accomplish this object and in most instances the sockets 10 have been provided with means to connect the socket to the body of the reflector including resilient means between the socket and the back of the reflector so that when the lamp is inserted therein, for replacement or otherwise, in each 15 instance the filament of the lamp will bear the same relation to the focus of the reflector.

It is an object of this invention to provide a fixed or prefocused socket rigidly held against the rear of the reflector and to provide means 20 upon the base of the lamp to rigidly engage the front of the reflector with the filament in proper relation to the focus and maintain the parts so assembled by resilient means in front of the reflector.

25 As will hereinafter be seen, it is a further object of this invention to assemble the usual annular flange upon the open end of the socket in contact with the rear of the reflector whereby when the socket is rigidly held in this manner, 30 a seal against the entry of dirt and moisture into the socket is provided.

With these and other objects in view, reference is made to the accompanying sheet of drawings which illustrate a preferred embodiment of this 35 invention with the understanding that minor changes may be made without departing from the scope thereof.

In the drawing:

40 Figure 1 is a view partly in central, vertical, longitudinal section through the center of the reflector and socket showing a lamp mounted therein in side elevation with the socket partly broken away showing parts in side elevation.

45 Figure 2 is a view in section taken on the line 2—2 of Figure 1 looking in the direction of the arrows.

50 Figure 3 is a view in section taken on the line 3—3 of Figure 1.

55 Figure 4 is a view in section taken on the line

4—4 of Figure 1 looking in the direction of the arrows.

Figure 5 is a view in section taken on the line 5—5 of Figure 1 looking in the direction of the arrows.

5 Figure 6 is an expanded view in perspective illustrating the lamp socket, the headlight reflector and the lamp in spaced apart relation.

In the embodiment of this invention as illustrated, the reflector 1 of the commercial headlight for an automobile is provided with a flattened section 2 about the circular opening 3 for the insertion of the base 4 of the lamp 5.

The socket to receive the lamp base 4 includes a cylindrical member 6 having an outstanding 15 annular flange 7 at one end and supports a plug 8 of Bakelite at the other end provided with two spaced apart cylindrical passageways parallel to the axis of the member 6 to slidably mount the terminals 9 of the wires 10 of the lighting 20 system. As customary in such constructions, the terminals 9 are provided with enlarged heads upon the interior of the socket with a coil spring 25 interposed between each head and the block 8 to maintain the terminals of the wires in contact 30 with the terminals of the lamp when inserted in the socket.

The flange 7 supports three spaced apart locking pins 11 which are rigidly attached thereto, as shown in Figures 1 and 3. Each pin axially 35 mounts a locking sleeve 12, the walls of which are spaced apart from the sides of the pin and are conically tapered at the end adjacent the flange 7 to slidably engage the pin. The free end of each pin 11 is provided with an enlarged 40 head 13 reciprocable within the sleeve 12 and a coil spring 14a is mounted about each pin 11 having one end bearing upon the under side of the head 13, and the other against the conical end of the sleeve to cause the sleeve 12 to firmly 45 engage the adjacent surface of the flange 7.

As shown in Figures 4 and 6, the flat portion 2 of the reflector 1 about the opening 3 is provided with three cylindrical openings 14 positioned to allow the locking sleeves 12 upon the flange 7 45 of the socket 6 to pass therethrough. Each of the openings 14 is provided with a restricted extension 15 adapted to allow of a rotative movement of the socket 6 with the extensions 15 receiving the bodies of the pins 11 and at the same time forcing the locking sleeves upward against the tension of the springs 14a so that when the pins 11 are at the ends of the extension 15, the sleeves 12 firmly engage the front of the reflector and hold the flange 7 rigidly against 55

the rear or back of the reflector. In order to removably secure the socket in its locked position upon the back of the reflector the flange 7 is provided with struck up tongues 16 adjacent 5 each pin 11 and so positioned that when the socket has been rotated to the positions shown in Figure 4 the tongues 16 will engage the opposite sides of the openings 14.

The lamp base 4 is provided with a sleeve 17 10 having an outstanding annular flange 18, as shown most clearly in Figure 6. The flange 18 is provided with three slots 19 elongated in the path of a circle concentric to the flange having one end 20 of circular formation of sufficient 15 size to allow the lamp base flange 18 to be inserted over the locking sleeves 12 and to allow a rotation of the lamp base when the flange is in contact with the flat front portion of the reflector to force the locking sleeves 12 upwardly 20 against the tension of their springs 14a during the rotation. The other end 21 is of circular 25 formation of sufficient size that when the lamp has been rotated the conical end of the locking sleeve 12 will engage the circular sides of the end 21 and firmly hold the lamp in fixed relation to the socket and in contact with the front side of the reflector 1.

The cylindrical surface of the member 6 of the socket is preferably knurled to assist in the 30 rotation of the socket after the locking sleeves 12 have been inserted from the rear through the reflector 1 until the tongues 16 snap into the openings 14. In this position, the socket pins 11 rigidly carried upon the socket flange 7 are in 35 engagement with one end of the openings 14 in the reflector body with the abutment end of the socket flange tongues 16 in engagement with the opposite end of said openings and the flat surface of the socket flange 7 is held in rigid 40 engagement with the flattened surface 2 about the opening 3 in the reflector by the tension of the locking sleeves 12 engaging the outer surface of the reflector so that it requires the exertion of sufficient force to overcome simultaneously 45 the combined resistance of the three springs 14a to withdraw the socket flange 7 away from the reflector to clear all of the abutting ends of the tongues 16 before the socket can be detached from the reflector. Lamps may be assembled 50 and disassembled with the socket in place with much less effort, and the rigid connection between the socket flange and rear of the reflector will not be disturbed as the conical ends of the locking sleeves 12 exercise a simultaneous 55 wedging action to compress the springs 14a when the lamp is rotated to cause the conical ends of the locking sleeves 12 to enter or be removed from the restricted circular ends 21 of the openings 20 in the lamp flange 18.

60 As shown in the embodiment of this invention, the lamp 5 is of the customary two filament type and to assure that the two terminals in the lamp base from the respective filaments register in contact with the two terminals 9 of the wires 10 of the lighting system, it is necessary to so locate the locking pins 11 that when the lamp base 4 has been inserted in the socket and rotated to the locked position the terminals of the lamp are in contact with the terminals 65 of the wires. In order that the lamp 5 may be replaced and assume the proper position, it is preferable to arrange two of the locking pins 11 at a lesser distance from each other on the flange 7 than the distance between the third pin 70 11 to either of the said pins. As the slots 19

in the flange 18 of the lamp base 4 register with the locking sleeves 12 on the pins 11, if the two most adjacent pins 11 are arranged at the top of the opening 3 in the reflector and the space between the most adjacent slots 19 in the lamp 5 flange 18 is marked "Top" the proper position of the lamp for the insertion is readily indicated.

From the above, it is readily seen that this improved mounting means allows an assembly of the socket upon the rear of the reflector to form a seal for the socket and the mounting of the spring pressed locking sleeves on pins rigidly carried on the socket flange. The mounting of the locking sleeves on the front of the reflector allows the ready assembly or removal of a lamp 10 without breaking said seal, eliminates strain tending to bend the socket pins as the lamp flange engages the part of the pins adjacent their rigid attachment to the socket flange, and also eliminates binding of the lamp flange in passing 15 into and out of its properly assembled position, and eliminates the tendency to break the lamp in the operator's hand which occurs where excessive pressure must be applied in assembling or disassembling a lamp. It also insures a consistent 20 positioning of the lamp in the correct 25 position upon assembly.

What I claim is:

1. A lamp assembly for a headlight comprising a lamp, a curved reflector with an opening for 30 receiving the lamp base and a flattened surface thereabout, a cup shaped socket for the reception and electrical connection to the lamp, an integral flange upon one end of the socket adapted to closely engage the rear of the flat surface of the reflector, a flange about the lamp base adapted to closely engage the front of the flat surface of the reflector when the base is inserted in the socket, a plurality of locking pins rigidly secured at one end upon the socket flange, 35 openings provided in the reflector and lamp base flange to receive the locking pins, and spring pressed means mounted upon the free ends of said pins to engage the outer side of the lamp base flange for detachably holding the said 40 flanges in close contact with opposite sides of the reflector when the lamp has established the electrical connection within the socket.

2. A lamp assembly for a headlight comprising a lamp, a curved reflector with an opening for 50 receiving the lamp base and a flat surface thereabout, a cup shaped socket for the reception and electrical connection to the lamp, an integral annular flange upon one end of the socket adapted to closely engage the rear of the 55 flat surface of the reflector, an annular flange about the lamp base adapted to closely engage the front of the flat surface of the reflector when the base is inserted in the socket, and means for detachably holding the said flanges 60 in contact with opposite sides of the flat surface of the reflector when the lamp base has been inserted to establish the electrical connection within the socket including a plurality of spaced apart locking pins rigidly mounted on the socket 65 flange, spring pressed retractable locking sleeves mounted on each of said pins, and apertures provided in the reflector and lamp base flange for the passage of the locking pins and locking sleeves therethrough.

3. The structure of claim 2, wherein the said locking sleeves are provided with conical ends adjacent the socket flange, and wherein the free ends of the said locking pins are provided with enlarged heads to guide the locking sleeves. 70 75

4. A lamp assembly for a headlight comprising a lamp, a curved reflector with an opening for receiving the lamp base and a flattened surface thereabout, and a cup shaped lamp socket having an integral annular flange about the open end adapted to be held in engagement with the flat surface upon the rear of the reflector, an annular flange upon the base of the lamp adapted to be held in engagement with the flat surface upon the front of the reflector with the electric terminals of the lamp in electrical contact with the terminals within the socket, spaced apart locking pins rigidly secured at one end upon the socket flange, cylindrical spring pressed locking sleeves mounted on said pins having conical ends adjacent the socket flange, openings provided in the reflector to allow the passage of the locking sleeves therethrough, said openings having restricted extensions allowing the socket to be rotated to cause the conical ends of the locking sleeves to engage the reflector body about the restricted portions of the openings, tongues struck up on the socket flange adapted to engage the edges of the larger openings to prevent counter-rotation of the socket, openings provided in the lamp base flange to allow the passage of the locking sleeves therethrough, said openings having restricted extensions terminating in circular ends allowing the

lamp to be rotated to cause the conical ends of the locking sleeves to engage the edges about the circular ends of the restricted portions of the lamp base flange openings to hold the lamp detachably mounted upon the reflector with the 5 socket flange and lamp flange in contact with opposite sides of the reflector.

5. A lamp socket for a headlight assembly including a cylindrical shell, an integral annular flange at one end thereof, an air-tight closure at 10 the other end, spring pressed terminals mounted upon said closure and connected to the wires of the lighting system, spaced apart locking pins rigidly secured at one end upon the socket flange in prolongation of the open end of the socket, 15 locking sleeves having conical ends mounted upon said pins with the conical ends adjacent the said flange, enlarged heads on the free ends of said pins, coil springs mounted on said pins interposed between the enlarged heads and the conical ends of the locking sleeves, whereby the socket may be assembled upon the headlight reflector with the conical ends of the locking sleeves engaging the front of the reflector to hold the socket flange in contact with the rear of the 20 reflector to provide a seal between the reflector and interior of the socket.

FELIX J. WATTS.
